UNITED STATES PATENT OFFICE.

THOMAS J. HUGHES, OF SEATTLE, WASHINGTON.

REVERSING-GEARING.

1,384,388.

Specification of Letters Patent.

Patented July 12, 1921.

Application filed October 12, 1920. Serial No. 416,426.

To all whom it may concern:

Be it known that I, THOMAS J. HUGHES, a citizen of the United States, residing at Seattle, in the county of King and State of Washington, have invented certain new and useful Improvements in Reversing-Gearing, of which the following is a specification.

This invention relates to reversing gearing and has for its object to provide simple, 10 compact, durable and efficient mechanism whereby a driving member may be connected to a driven member for positively rotating the latter in the same or in opposite directions.

15 The invention consists in the novel construction, combination and arrangement of parts as hereinafter described and claimed.

An embodiment of my invention is illustrated in the accompanying drawings, 20 wherein—

Figure 1 is a longitudinal sectional view taken through 1—1 of Fig. 2, and Fig. 2 is an end elevational view with some of the parts broken away to disclose other parts 25 in the rear thereof.

In said drawings, the numeral 5 designates a primary shaft which may be rotated by any suitable driving means, and 6 is a secondary shaft which is driven from said 30 primary shaft through the instrumentality of gearing to be hereinafter described.

Said shafts are arranged parallel with each other and are shown as journaled in bearing boxes 5¹ and 6¹ provided in frame 35 plates 7 and 8 which are rigidly secured to a suitable support.

Keyed or otherwise secured to the secondary shaft 6 between said frame plates are two spur gears 9 and 10 of unequal diameters and herein shown as integral with each other. Surrounding the smaller gear 10 is a series of spur pinions 12 respectively mounted on studs 13 which are secured in spaced relations to the frame plate 7 so that 45 the pinions will be in mesh with the gear 10.

The pinions 12, in turn, are surrounded by a ring gear 14 of an external diameter equal to the diameter of the gear 9. This ring gear is provided about its outer periphery 50 with spur teeth 15 corresponding in number and sizes with those of the gear 9.

The ring gear 14 is interiorly provided with teeth 16 meshing with the teeth of the pinions 12, which latter serve to support the 55 ring gear and maintain the same concentric to the axis of the secondary shaft 6. Con-

nected for axial movements, as by a spline 17, to the primary shaft 5 is a sleeve 18 which is formed or provided with a gear element or pinion 19 which is selectively engageable with the teeth of gear 9 or with the external teeth 15 of said ring gear. As shown, the pinion 19 is shiftable by means of a bifurcated lever 20 fulcrumed at 21 to the frame plate 7 and is connected to the 65 sleeve 18 by means of a collar 22 which is rotatable in an annular groove provided in the sleeve.

Assuming that the pinion 19 is driven counter-clockwise and engages the ring gear 70 14 as shown in the drawings it will be apparent that the power is transmitted through the system of gears—14, 12, 10—as denoted by direction arrows in Fig. 2 to drive the shaft 6 in the same rotary direction as the 75 shaft 5.

When the pinion 19, however, is moved from its engagement with the ring gear into engagement with the gear 9 the shaft 6 is caused to be rotated in the opposite direction to the shaft 5.

It will of course be understood that the number of pinions 12 acting between the ring gear 14 and the smaller gear 10 on the secondary shaft 6 may be varied and that if 85 desired the duties of the primary and secondary shafts may be reversed, that is to say, the shaft 6 may be utilized as the driving member whereby motion is transmitted through the medium of the above described 90 gears for the purpose of rotating the shaft 5 in the same or opposite direction to that of the shaft 6.

The construction, operation and advantages of my improved reversing gearing 95 will, it is thought, be understood from the foregoing description.

What I claim is,—

1. In a reversing-gear, the combination of a frame, a shaft extending therethrough, 100 two gear-wheels of unequal diameters mounted upon said shaft, a gear-ring, a plurality of pinions rotatably connected to said frame and meshing with the smaller of said gear-wheels and the ring-gear to afford driving connections therebetween, a second shaft, a pinion rotatably mounted thereon, and means for moving the last named pinion to engage either the larger of said gear-wheels or the ring-gear. 105

2. In a reversing-gear, the combination of a frame, a shaft extending therethrough,

two gear-wheels of unequal diameters mounted upon said shaft, a gear-ring having a diameter equal to the larger of said gear-wheels, a plurality of pinions rotatably connected to said frame and meshing with the smaller of said gear-wheels and the ring-gear to afford driving connections therebetween and also serving to support the ring-gear concentrically to the axis of said shaft, a second shaft, a pinion rotatably mounted thereon, and means for moving the last named pinion to engage either the larger of said gear-wheels or the ring-gear.

3. In a reversing-gear, the combination of a frame, a shaft journaled therein, two gear-

wheels of unequal diameters mounted on said shaft, a ring-gear having an external diameter equal to the larger of the aforesaid gear-wheels, a series of pinions rotatably connected to said frame and operatively connecting the smaller of said gear-wheels to said ring-gear, and driving means engageable with the larger of said gear-wheels or the ring-gear selectively. 20

Signed at Seattle, Washington, this 2nd 25
day of October, 1920.

THOMAS J. HUGHES.
